US00D804957S

(12) **United States Design Patent** (10) **Patent No.:** **US D804,957 S**
(45) **Date of Patent:** **** Dec. 12, 2017**

(54) **SPRAYER**

(71) Applicant: **MAXWELL MAGNETOELECTRICITY TECHNOLOGY CO., LTD**, London (GB)

(72) Inventor: **Zhaoxu He**, Ningbo (CN)

(73) Assignee: **Maxwell MagnetoElectricity Technology Co., Ltd.**, London (GB)

(**) Term: **15 Years**

(21) Appl. No.: **29/566,059**

(22) Filed: **May 26, 2016**

(51) LOC (10) Cl. **09-01**

(52) U.S. Cl.

CLAIM

The ornamental design for a sprayer, as shown and described.

DESCRIPTION

FIG. 1 is a top, front, right perspective view of a sprayer showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a top, rear, right perspective view thereof; and,

FIG. 9 is bottom, front, left perspective view thereof.

1 Claim, 8 Drawing Sheets
